UNITED STATES PATENT OFFICE.

CHARLES LEVY ZIMMERMAN, OF EL PASO, TEXAS.

ACCOUNT-BOOK.

1,186,872.

Specification of Letters Patent. Patented June 13, 1916.

Application filed October 1, 1914. Serial No. 864,375.

To all whom it may concern:

Be it known that I, CHARLES LEVY ZIMMERMAN, a citizen of the United States of America, residing at El Paso, in the county of El Paso and State of Texas, have invented certain new and useful Improvements in Account-Books, of which the following is a specification.

This invention relates to accounting systems, and has particular reference to a system of voucher or journal records in which the totals of the debits and credits can be examined and checked at a glance.

The primary object of my invention is to provide an accounting system which can be used in connection with a series of sheets which are assembled in a suitably constructed book form or loose leaf binder or cover, the several sheets having a definite relation 20 to one another whereby totals of debits or credits may be accurately, and substantially instantaneously checked or distributed, or may be distributed rapidly into all items of expenditure or credit without reference to a 25 series of books or individual accounts.

Furthermore, it is an object of the present invention to so bind a plurality of sheets together that the several sources of debit or credit and the several sub-sources of the latter may be readily ascertained from a single 30 set of the sheets in a concise and simplified manner.

More particularly, it is the object of this invention to provide an accounting system 35 comprising main debit and credit sheets having means for indicating the general headings of expenditure or credit and a series of related sub-sheets containing sub-headings of distribution under the general headings 40 above mentioned, the binding of the leaves or sheets being such that each set of sub-headings on a particular sub-sheet may be brought into visible sub-relation to its general heading on the main debit or credit 45 sheet so that the distribution of the total under the general heading can be readily ascertained or checked.

With the above and other objects which will hereinafter appear in view, my invention 50 will now be fully set forth and described, reference being had to the accompanying drawing, in which—

Figures 1 and 1^a represent continuously 55 the main debit sheet, which also constitutes the totals of debit headings of a voucher record; Fig. 2 represents the main credit

sheet which also constitutes the totals of credit heading of a voucher record; Fig. 3 shows one of the sub-sheets containing the distribution of the debit or credit amount 60 entered under one of the general headings contained on one of the main sheets; Figs. 4, 5, 6, 7, 8 and 9 show similar sheets referring to other headings; Fig. 10 shows a preferred method of binding the various sheets; 65 Fig. 11 is a fragmentary top plan of a main sheet having a sub-sheet superposed thereon; Figs. 12 and 13 are views indicating the method of providing for a plurality of sub-sheets or distributing sheets under any one 70 general heading.

The well known system of keeping books in which a separate journal entry of each individual transaction and a posting of each individual entry in the ledger is required entails a great deal of unnecessary work. A 75 voucher record system is known which shows the ledger headings, with separate auxiliary books for making the distributions of ledger headings. Also, voucher sheets containing 80 records of the general ledger headings, or ledger accounts, showing the debit and credit entries to such headings, are now in use, and some voucher records contain also in addition to the debit entries an entirely different 85 manner of distribution of general debit headings of accounts; but none as known to me have as yet been entirely practical and none show the distributions of both debits and credits in the simple and easily checked 90 and balanced manner hereinafter described.

While my invention is applicable to any accounting system, such as material or manufacturing records, store house records, railroad or tonnage records, for the purpose 95 of the present application I have shown the system as a voucher record.

Referring more particularly to the drawings, Figs. 1—1^a, 1 indicates a main debit sheet, and since this sheet forms the foundation upon which the remaining sheets of the system are based, it also constitutes a record of entries. Thus, for the particular voucher record to which I have applied my system, the main sheet 1 is provided at the left hand 100 end with a plurality of columns for recording the titles, dates, numbers and other necessary data for identifying the vouchers. To the right of this data appears a column 105 in which is placed the total of the voucher. The distribution of the total just mentioned is indicated by the columns which appear to 110

the right of the total column and which are headed "Mining," "Development," "Milling," etc. While the distributions under the general headings just mentioned may indicate either the debit or credit items of the voucher, on the sheet represented, they are indicated as debit items.

Referring to Fig. 10, it will be noted that the sheet 1 is at the bottom of the binding 10 and is the longest of any of the sheets in the sets which constitute a complete record. The sheet 2 which is bound to the sheet 1 at their right hand ends, is a credit sheet corresponding to the debit sheet 1, and contains 15 the several general headings "Accounts payable", "Accounts receivable", "Store", etc. Said sheet 2 extends to the left in such relation to the sheet 1 that its left hand edge coincides with the right hand side of the 20 total column 3 of sheet 1. Thus, the voucher data contained on the left hand portion of sheet 1 refers also to the heading on the sheet 2, and since the total of the debits and credits must be the same, the total of column 25 3 of sheet 1 not only represents the total of the general headings of the debits on sheet 1 but also the total of the credits on sheet 2. The relation of sheets 1 and 2 in their bound condition is best indicated in Fig. 10.

30 Thus, in my system of voucher record the arrangement is such that the total of the debits and credits of each entry can be seen and checked at a glance, to agree with the total amount of each voucher, and at the 35 period or end of the month the totals of each general heading as shown on the main debit and credit sheets, can be made by one entry in the journal and then from the journal posted in the ledger, or posted direct 40 from voucher record into ledger.

The sub-sheets or interleaves represented in Figs. 3 to 9 constitute the distribution sheets upon which are indicated the various items which go to make the totals represented under the general headings "Mining", 45 "Developing", etc., indicated on the main sheets 1 and 2. Said sub-sheets are divided into two sets one of which is bound on top of the main sheet 1, and constitute the sub- 50 debit headings into which the several debit headings on sheet 1 are distributed. The other set is bound on top of the main credit sheet 2, and provides the sub-headings for the distribution of the totals carried under 55 the general headings of the credit sheet.

Fig. 3 indicates the topmost and longest sub-sheet or inter-leaf 4, said sheet 4 being bound at its right hand end and extending to the left, with its free end on a line with 60 the right hand side of the first general heading column of the debit sheet 1, said column in the present instance being designated "Mining". The sheet 4 bears the same heading as the general heading on sheet 1 to 65 which it refers, and any particular or specific

heading which is required. Thus, sheet 4 is headed "Mining—San Miguel". The various headed columns on this sheet represent the sub-divisions of expenditure which make up the total indicated under its respective 70 general heading on sheet 1.

The next sheet 5 below the sheet 4 is shorter than the latter by the width of the second column "Development" of the main sheet 1, and bears that heading, together 75 with the suitable specific denominations. The various columns on this sheet also represent the sub-head of expenditure or debit which are totalized on the main sheet 1 under the general headings "Development". 80 This system is followed out with the remaining sheets 6, 7 and 8.

In the construction of the sheets it is provided that the general headings whose credits or debits are broken up under the 85 greatest numbers of sub-heads will occur farthest to the left of the main sheet 1, and are graded down until the general headings having the smallest number of sub-sources of distribution will appear at the 90 right of the main sheet 1, so that the shortest sheets, as represented by sheets 7 and 8 in Fig. 10 may take care of those general headings on sheet 1 which require the least number of sub-divisions of the general heading 95 totals to show its complete distribution. A set of sheets substantially identical with those described as the debit sub-sheets or inter-leaves are bound on top of the main sheet 2, and provide for the sub-division or 100 distribution of the general heading totals carried on the credit sheet 2. Thus, for each voucher, either for its debit or its credit side, a complete exposition of its items may be made by a proper coincidence of main sheet 105 1 with the various sub-sheets 4, 5, 6, 7 or 8 or a proper coincidence of the voucher data columns of sheet 1 with the credit sheet 2 and its several sub-sheets as represented by 9 and 10 of Fig. 10.

When it becomes necessary to provide 110 duplicate sheets for any general heading, so that more than one sheet of a given length is placed next to a general heading column, it becomes necessary also to provide means for showing the total of all such sheets so that the proper coincidence between the debit and credit totals of the several sheets may be readily accomplished. Figs. 12 and 13 show such duplicate sheets, 115 said sheets being provided with total columns at their left hand ends at the outside of the first sub-heading of the sheet. It is evident that the bottom and top sheets and all interleaved or sub-sheets may be used in 120 duplicate, triplicate or in any multiple combination by carbon copies, paste-board, oil or other suitable material being used between the sheets containing the several accounts, and the different divisions can be 125 130

properly indexed to permit a ready access to the different accounts.

The same general arrangement of sheets can be used for a yearly record of general 5 headings and distributions by transferring from the periodical or monthly records the totals of all and each of the columns on general headings of the main debit and credit sheets, and also the distributions of the accounts 10 on all interleaved sheets, so that at the end of the year, a complete recapitulation can be made of all general accounts and distributions that are shown on each monthly or periodical account.

15 The use of my improved accounting system has been brought out in the description of the case, and a rehearsal of its operation at this time is not believed necessary.

What is claimed is:

- 20 1. An account book including a main entry sheet having a plurality of columns thereon, and a series of sub-sheets secured on the main sheet, each sub-sheet being longer than the next lower sub-sheet by the 25 width of a column and adapted for association with the column of the main sheet at which it terminates.
2. An account book comprising a main entry sheet having a plurality of columns 30 thereon each of which designates different accounts, a series of sub-sheets arranged on the main sheet, and means securing the sheets together, each sub-sheet being longer than the next lower sub-sheet by the width 35 of the column underlying said specified longer sheet only, each sub-sheet being provided for an itemized statement of the account column adjacent the free edge of said sub-sheet and extending outwardly there- 40 from.
3. An account book comprising a main sheet having a plurality of columns, a series of sheets arranged on the main sheet, each sheet of the series being adapted for association 45 with a respective column of the main sheet and the lowermost sheet of the series being the shortest with the superposed sheets being longer in progressive order there- from.
- 50 4. An account book comprising a main entry sheet having a total column and a plurality of other columns extending from one side of the total column, a series of sub-sheets secured to the main sheet adjacent the 55 remote column of the plurality of columns,

which latter designate different accounts, and each sub-sheet representing an itemized statement of a respective column of the main sheet, the lowermost sub-sheet having its free edge lying substantially at the edge 60 of the column of the main sheet which is remotest from the total column and each succeeding sub-sheet having its free edge extending over the next lower sub-sheet the width of the underlying column of the main 65 sheet whereby said last free edge will lie substantially even with the edge of the next column, a second main sheet secured to the series of sub-sheets and having its free edge arranged in coincidence with the total column of the first main sheet, said second main sheet also being provided with columns designating different accounts, and a second series of sub-sheets secured to the 70 second main sheet, the lowermost sub-sheet 75 of the second series having its free edge in coincidence with the column remotest from the free edge of the second main sheet and each succeeding upper sub-sheet extending over the free edge of the next lower sub- 80 sheet the width of a column, each sheet of the second series representing an itemized statement of the account contained in the respective column of said second main sheet with which the free edge of the sub-sheet 85 is in coincidence.

5. An account book comprising a main entry sheet having a total column and a plurality of other columns, a second main entry sheet disposed over the first sheet and 90 adapted to have its outer edge portion lie in direct contact with the latter and in coincidence with the total column, said second sheet being provided with columns, a series of sub-sheets, one for each of the other 95 columns, arranged between the main sheets and adapted to have the outer edges of the sub-sheets lie in direct contact with the first main entry sheet and in coincidence with the respective other columns, and a second 100 series of sub-sheets arranged on the second main sheet and each being adapted for association with a respective column thereon.

In testimony whereof I affix my signature in presence of two witnesses.

CHARLES LEVY ZIMMERMAN.
